(57) **CLAIM**

We claim the ornamental design for a sliring/locknut combination piece for use in a powered tap assembly, as shown and described.

DESCRIPTION

FIG. 1 is a perspective view showing our new design for a sliring/locknut combination piece for use in a powered tap assembly.

FIG. 2 is an alternative perspective view of our new sliring/locknut combination piece.

FIG. 3 is a top view of our new sliring/locknut combination piece; and,

FIG. 4 is a side view of our new sliring/locknut combination piece.

The broken lines are for environmental purposes only and form no part of the claimed subject matter.
